Primary Examiner — Sheryl Lane*Assistant Examiner* — Mark T. Philipp*(74) Attorney, Agent, or Firm* — Gregory L. Mayback; Dickinson Wright PLLC(57) **CLAIM**

The ornamental design for a vacuum pump, as shown and described.

DESCRIPTION

FIG. 1 is a top perspective view of a vacuum pump showing our new design;

FIG. 2 is a top plan view thereof;

FIG. 3 is a left side elevation view thereof;

FIG. 4 is a front elevation view thereof;

FIG. 5 is a right side elevation view thereof;

FIG. 6 is a rear elevation view thereof; and,

FIG. 7 is a bottom plan view thereof.

The depictions within the broken lines are for the purpose of illustrating portions of the vacuum pump that form no part of the claim.

1 Claim, 3 Drawing Sheets(56)
